UNITED STATES PATENT OFFICE.

ALBERT H. McALLISTER, OF NEW ALBANY, MISSISSIPPI.

DESIGN FOR A NUT-LOCKING WASHER.

SPECIFICATION forming part of Design No. 31,242, dated July 18, 1899.

Application filed June 23, 1899. Serial No. 721,646. Term of patent 7 years.

To all whom it may concern:

Be it known that I, ALBERT H. McALLISTER, a citizen of the United States, residing at New Albany, in the county of Union, State of Mississippi, have invented and produced a new and original Design for Nut-Locking Washers, of which the following is a specification, reference being had to the accompanying drawings, forming part thereof.

Figure 1 shows one of the broader faces of the washer. Fig. 2 is an edge view looking in the direction of the arrow of Fig. 1.

As shown in the drawings, the washer embodying my novel design is a plate diamond-

shaped in general outline, centrally perforated at B, and having one of its longer points bent upward or out of the plane of the body of the plate. This form characterizes my design.

Having described my invention, what I claim as new, and desire to secure by Letters Patent, is—

The design for a nut-locking washer, substantially as shown and described.

ALBERT H. McALLISTER.
